United States Patent Office

Des. 202,408
Patented Sept. 28, 1965

202,408

INDEX TAB HOLDER

Walter Feldmahr, Oceanside, N.Y., assignor to Natser Corporation, Ogdensburg, N.Y., a corporation of Nevada, doing business as Acco Products, Ogdensburg, N.Y.

Filed Aug. 3, 1964, Ser. No. 81,150

Term of patent 14 years

(Cl. D1—3)

FIG. 1 is a perspective view of an index tab holder showing my new design;

FIG. 2 is an elevational view of one side thereof;

FIG. 3 is an end elevational view thereof;

FIG. 4 is an elevational view of the other side thereof; and

FIG. 5 is a bottom plan view thereof.

I claim:

The ornamental design for an index tab holder, substantially as shown.
